(57) **CLAIM**

The ornamental design for a display screen with animated graphical user interface for vehicle taillight, as shown and described.

DESCRIPTION

FIG. 1 is a first image in a sequence for a display screen with animated graphical user interface for vehicle taillight showing my new design; and,

FIG. 2 is a second image thereof.

The broken lines showing an electronic device illustrate environmental subject matter. The broken lines showing a display screen and elements of the graphical user interface illustrate portions of the article. None of the broken lines form part of the claimed design.

The appearance of the graphical user interface transitions sequentially between the figures. The process or period in which one image transitions to another forms no part of the claimed design.
